CLAIM

The ornamental design for an electrical load control panel, as shown and described.

DESCRIPTION

FIG. 1 is a front plan view of an electrical load control panel showing our new design;

FIG. 2 is a right side elevational view of FIG. 1;

FIG. 3 is a left side elevational view of FIG. 1;

FIG. 4 is a top plan view of FIG. 1;

FIG. 5 is a bottom plan view of FIG. 1;

FIG. 6 is a front plan view of our new design wherein a door which normally covers certain controls is shown in an open position, exposing the controls to view;

FIG. 7 is a right side elevational view of FIG. 6; and,

FIG. 8 is an isometric view of FIG. 6.

FIG. 4

FIG. 5

FIG. 2

FIG. 1

FIG. 3

FIG. 8

FIG. 7

FIG. 6
